PLLC; Joann M. Seaton

(57) **CLAIM**

We claim the ornamental design for a combined tag with
band, as shown and described.

DESCRIPTION

FIG. 1 is a front, perspective view of the first embodiment
of a combined tag with band, showing our new design;
FIG. 2 is a rear, perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and

FIG. 8 is a bottom view thereof.

FIG. 9 is a front, perspective view of FIG. 1 shown in an
environment of use;

FIG. 10 is a front view thereof;

FIG. 11 is a back view thereof;

FIG. 12 is a right side view thereof;

FIG. 13 is a left side view thereof;

FIG. 14 is a top view thereof; and

FIG. 15 is a bottom view thereof.

FIG. 16 is a front, perspective view of the second embodiment
of a combined tag with band, showing our new design;

FIG. 17 is a rear, perspective view thereof;

FIG. 18 is a front view thereof;

FIG. 19 is a rear view thereof;

FIG. 20 is a right side view thereof;

FIG. 21 is a left side view thereof;

FIG. 22 is a top view thereof; and

FIG. 23 is a bottom view thereof.

FIG. 24 is a front, perspective view of FIG. 16 shown in an
environment of use;

FIG. 25 is a front view thereof;

FIG. 26 is a back view thereof;

(Continued)

FIG. 27 is a right side view thereof;
 FIG. 28 is a left side view thereof;
 FIG. 29 is a top view thereof; and,
 FIG. 30 is a bottom view thereof.

The evenly spaced broken lines in the figure drawings show environment and form no part of the claimed design. The dot-dash broken lines define the bounds of the claimed design and form no part thereof.
